UNITED STATES PATENT OFFICE.

ROBERT V. BINGAY, OF PITTSBURGH, PENNSYLVANIA, ASSIGNOR TO PITTSBURGH TRANSFORMER COMPANY, A CORPORATION OF PENNSYLVANIA.

TRANSFORMER TANK.

Application filed January 15, 1923. Serial No. 612,604.

This invention relates to tanks for transformers and similar apparatus adapted to be submerged in cooling and insulating oil, and particularly to the part of the container 5 covering the surface of the oil in such tanks. Hitherto it has been the practice to leave these parts over the surface of the oil exposed on the outside to the air for additional cooling effect. This, however, in 10 many cases and particularly in transformers installed outdoors results in a condensation of moisture within the top of the main tank or expansion tank over the surface of the oil whenever there is sudden cooling. This 15 condensed moisture may eventually find its way into the oil with impairment of the insulating strength of the oil.

The object of this invention is to avoid 20 this objectionable condensation of moisture by protecting the tank parts over the oil from sudden cooling.

In the accompanying drawings

Fig. 1 is a vertical sectional view of a transformer having its top covered with heat 25 insulating material in accordance with this invention, and

Figs. 2 and 3 are sectional views of a modification illustrating the application of the heat insulating material to a separate 30 expansion tank, the main tank being filled with oil without an upper exposed surface.

In the specific embodiment of the invention shown in Figure 1 a transformer tank 4 having a top ring flange 5 is provided 35 with a cover 6 having a manhole 7 with an independently removable top 8. Various openings through the cover are provided for the leads and frame rods as indicated at 9-9 and the cover 6 is held to the flange 5 40 by clamps 10. The transformer indicated by dotted lines at 20 resting on the bottom of the tank is immersed in oil which fills the tank to the lever 11 and when the transformer is in service this oil becomes heated 45 and the air space 12 above it also becomes heated and contains air which is more or less moist. If now there is a sudden chilling of the cover 6 as by a shower the moisture of the air in the space 12 will condense underneath the cover surfaces and this moisture may eventually find its way to a large 50 extent into the tank oil.

To avoid any such sudden chilling of the metallic surfaces of the air space 12 layers 55 or lagging 14, 15 of heat insulating mate-

rial are provided over the exposed surfaces of the cover 6 and top 8 as shown. These surfaces are thus maintained protected against sudden chilling from the outside and thus the deposit of moisture from the 60 air in space 12 is avoided, the inner surfaces of the cover being maintained sufficiently warm to prevent this condensation of moisture. The cooling of the oil will be practically entirely taken care of by the tank surfaces in direct contact with the oil in most 65 efficient manner and the deposit and accumulation of moisture by sudden chilling of the air space surfaces will be avoided. Instead of the lagging 14, 15 the heat insulation may be provided in any desired manner such for instance as by air pockets or 70 layers of fabric.

In the modification shown in Figs. 2 and 3 the main tank T is filled with oil up to its 75 very top and the oil overflows or expands into the expansion tank t connected to the main tank T by the pipe 15'. This expansion tank t has a liquid level gauge 16 and a breather 17 maintaining communications 80 between the outside air and the surface of the oil in the expansion tank. All of the surfaces of the expansion tank t that are or are likely to be in contact with the space over the surface of the oil are covered with 85 heat insulating material or lagging 19 so that this space above the oil in the expansion tank is kept protected against sudden cooling.

While the invention has been described 90 in connection with specific embodiments it is not confined thereto but is intended to cover such modifications thereof as fall within the scope of the appended claim.

I claim:

In combination a transformer tank containing oil and a transformer or similar intermittent heat radiating apparatus therein and having uncovered vertical side surfaces adapted to cool said oil to prevent undue 100 rise in temperature, an air space being provided above the surface of said oil in said tank, a cover having a metal under surface covering said air space, and heat insulating material on the surface of said cover to avoid premature chilling of the top surface of said air space and prevent condensation of moisture on said surface during cooling of said transformer.

ROBERT V. BINGAY.
